UNITED STATES PATENT OFFICE.

EUGENE L. MC GUIRE, OF DENNISON, OHIO, ASSIGNOR OF ONE-HALF TO ALEXANDER SALES, OF DENNISON, OHIO.

FEEDING AND REMOVING APPARATUS FOR FURNACES.

1,320,898.

Specification of Letters Patent.

Patented Nov. 4, 1919.

Application filed May 17, 1917. Serial No. 169,202.

To all whom it may concern:

Be it known that I, EUGENE L. MC GUIRE, citizen of the United States, residing at Dennison, in the county of Tuscarawas and 5 State of Ohio, have invented certain new and useful Improvements in Feeding and Removing Apparatus for Furnaces, of which the following is a specification.

My invention relates to heating apparatus 10 and more particularly to means for mechanically feeding the fuel thereto, removing the ash, and regulating the drafts.

One of the objects is to provide mechanism of this class adapted primarily to permit 15 a heating apparatus or plant located in the basement to be operated from living rooms or other central point of the building and which will prevent dust and dirt.

Another object is to provide novel and 20 efficient means for controlling the operation of the different mechanism.

Generally stated, the invention comprises power means, combined with the furnace structure, and suitable conveyers, shafts, 25 drive connections, and control means whereby the furnace may be entirely operated and regulated from a distant point.

One preferred construction of the invention is illustrated in the accompanying 30 drawings, in which—

Figure 1 is a side elevation of a furnace embodying my invention, the furnace being partly broken away,

Fig. 2 is a front elevation of the same 35 partly broken away and showing the controlling means in detail, and

Fig. 3 is a detail view of one of the belt shifts employed.

Referring more particularly to the drawings, the numeral 2 designates the shell of 40 a furnace having a fire pot 3 and grate 4.

A drive shaft 5 is situated above the furnace and preferably hung from the ceiling by hangers 6 and is driven by a suitable 45 power such as the motor 7 or may be manually turned by means of the chain and sprocket mechanism 8.

The fuel is stored in a hopper 9 having an inlet entering a conveyer casing 10 having 50 a conveyer 11 trained about pulleys 12, 13 and 14 therein. The pulley 14 is mounted on a shaft 15 and is connected with the drive shaft 5 by a belt 17 trained over pulleys 16 and 18. An idler pulley 19 is mounted adjacent the pulley 18 for a purpose to be de-

scribed. The conveyer casing 10 enters the fire-pot and has its inner end closed by a flap door 20 and also has a slide door 21 to cut off the coal supply, the slide door 21 being operated by a member 22 having a 60 terminal 23 at any desired place.

Located within the fire-pot is a rocking grate 4 which is operated by suitable crank and link mechanism 24 connected to shaft 25 mounted in bearing 26 on support 27 65 and driven by belt 28 trained about pulleys 29 and 30. The pulley 30 is keyed to the shaft 5 and has an idler 31 mounted adjacent thereto.

The bottom of the fire-pot slopes downwardly to the rear forming a chute and converges to the exit 32 entering the conveyer casing 33 which terminates in a suitable outlet 34 which is preferably located at the exterior of the building. A conveyer 70 75 35 is trained about pulleys 36 and 37 within the casing 33 and is driven by a belt 38 trained about the pulley 39 on shaft 40 and pulley 41. The pulley 41 is keyed on the shaft 4 and has an idler 42 mounted adjacent thereto.

A sliding cut off door 43 is mounted in the exit 32 and operated similar to door 21 in casing 10 by a member 44 having terminal 45.

Slidably mounted in hangers 46 are belt shifts 47 having shifting arms 48 and flexible connecting members 49 secured to each end thereof and trained over sheave wheels 50 and connected to cranking wheels 51.

A belt shift 47 is provided for each of the belts 17, 28 and 38 and is adapted to shift the respective belts by a turn of the crank 51 onto their respective idlers thus making the desired parts inoperative.

The motor 7 supplying power to the main shaft 5 is controlled by a switch 52 adjacent the cranking wheels 51.

The draft entering the fire-pot 3 is controlled by a suitable door 53 adapted to be 100 raised or lowered by a flexible member 54 secured to crank 55.

The operation of my device is as follows:—The motor is started and the suitable crank 51 is turned to throw belt 17 on the 105 idler 19, the sliding door 43 is then raised by grasping the terminal 45 of member 44 and the ash will enter the casing 33 and be carried away by the conveyer 35. The ash having been removed, the door 43 is 110

lowered and suitable cranking wheels 51 are turned to throw belts 28 and 38 on their respective idlers and belt 17 from idler pulley 19 to pulley 18; the conveyer 11 will then be in operation and the slide door 21 is then raised by grasping the terminal 23 of the member 22 permitting the fuel to enter the fire-pot.

It will be obvious that I have provided 10 a control system and the mechanism for carrying it out that will eliminate all the objectionable labor for caring for a furnace.

It will also be obvious that various 15 changes in construction may be made from time to time to accommodate the many different forms of furnaces and although I have shown and described a preferred form of my invention I do not wish to be limited to that construction since the above and 20 other minor changes in construction may be readily made without departing from the spirit of my invention as defined in the appended claims.

Having thus described my invention, what 25 I claim is:

1. In feeding and removing apparatus for furnaces comprising a furnace having a shaking grate and actuating mechanism therefor having a pulley, a fuel feeding device 30 having a pulley, an ash removing conveyer having a pulley, a power driven shaft having a series of pairs of tight and loose pulleys and individual shifting belts connecting said pulleys with the pulley of the grate 35 actuating mechanism, the fuel feeding device and the ash removing conveyer, respectively, and a separate individual belt shifting device for each of said belts, said several elements being located in a separate sub- 40 chamber or compartment, the combination therewith of a separate individual flexible actuating mechanism connected with each belt-shifting device, guiding sheaves therefor, and separate individual operating 45 cranking wheels located in said separate compartment and connected with each of said flexible actuating mechanisms respectively, substantially as set forth.

2. In feeding and removing apparatus for 50 furnaces comprising a furnace having a shaking grate and actuating mechanism therefor having a pulley, a fuel feeding device having a pulley, an ash removing conveyer having a pulley, a power driven shaft

having an auxiliary hand-actuated operating mechanism and a series of pairs of tight and loose pulleys and separate individual shifting belts connecting said pulleys with the pulley of the grate actuating mechanism, the fuel feeding device and the ash removing conveyer, respectively, and a separate individual belt shifting device for each of said belts, said several elements being located in a separate sub-chamber or compartment, the combination therewith of flexible actuating mechanism connected with each belt-shifting device, guiding sheaves therefor, and individual isolated operating cranking wheels located in said separate compartment and connected with each of said flexible actuating mechanisms respectively, substantially as set forth.

3. In feeding and removing apparatus for furnaces comprising a furnace having a shaking grate and actuating mechanism therefor having a pulley, a fuel feeding device having a pulley, an ash removing conveyer having a pulley, a power driven shaft having a series of pairs of tight and loose pulleys and individual shifting belts connecting said pulleys with the pulley of the grate actuating mechanism, the fuel feeding device and the ash removing conveyer, respectively, and a separate individual belt shifting device for each of said belts, a motor and gearing connecting it with the power shaft, said several elements being located in a separate sub-chamber or compartment; the combination therewith of flexible actuating mechanism connected with each belt-shifting device, guiding sheaves therefor, individual isolated operating cranking wheels connected with each of said flexible actuating mechanisms respectively, an auxiliary hand-actuated operating mechanism connected with the power shaft, and a controlling switch in circuit with the motor, said cranking wheels, hand-actuated operating mechanism, and controlling switch being located in said separate compartment and in convenient juxtaposition for individual operations, whereby either may be used independently of the others, substantially as set forth.

In testimony whereof I heretunto affix my 105 signature.

EUGENE L. McGUIRE.
